UNITED STATES PATENT OFFICE.

AUTHUR J. SHAW, OF SPOKANE, WASHINGTON.

CATTLE GUARD.

Application filed July 21, 1924. Serial No. 727,278.

The present invention relates to improvements in cattle guards for use on railways for the purpose of preventing cattle, horses or stock from trespassing upon or passing over the railway tracks, causing damage and derailments. The guard is of the rotary type, and is especially designed in sections or standard units and parts adapted to the standard railway road bed in order that the appliance may with facility be placed in position and with equal facility may be removed when required, as for the purpose of making necessary repairs to the tracks or roadbed.

The primary object of the invention is the provision of a device of this character which is comparatively inexpensive in cost of production and in which the parts are interchangeable; which is simple in construction, and, as it comprises a minimum number of parts which are comparatively light in weight, may be handled by a single track-hand or other individual.

The invention consists in certain novel combinations and arrangements of parts as will hereinafter be more fully pointed out and claimed. In the accompanying drawings I have illustrated one complete example of the physical embodiment of my invention in which the parts are combined and arranged in accord with the best mode I have thus far devised for the practical application of the principles of my invention. It will be understood, however, that different arrangements of the standardized units or sections may be used other than that illustrated, and the appliance is applicable for use at various places along the railroad, as for instance on bridges and tunnels, or on the approaches thereto.

Figure 1 is a plan view of a portion of a railway showing portions or sections of the complete cattle guard, and showing also uncompleted portions of the guard for convenience of illustration.

Figure 2 is an enlarged detail end view of a portion of one of the intermediate units or sections used between the rails of the track, and showing the relation thereto of the track rail.

Figure 3 is a view in side elevation of a portion of one of the rotary guards.

For a ready understanding of the invention I have indicated a portion of a railway track of standard gage and including the track rails 1 and cross ties 2. In as-

sembling the appliance two outer or track-side units 3 and 4 are usually alined with an intermediate unit 5 located between the rails.

The trackside units or frames 3 and 4 may be of metal and are of oblong shape to lie parallel with the tracks as indicated in Figure 1. The greater dimension or length of these trackside frames corresponds to the length and width of the square, intermediate frame 5 which is located between the tracks or track rails, and other features common to both the trackside and intermediate frames will appear hereinafter.

The frames are all open, rectangular structures, and each frame is provided, as at its four corners, with a perforated lug or ear 6 through which a spike or bolt 7 is passed to securely anchor the frame to the cross ties.

The trackside frames 3 and 4 each have provided in their end bars 8, a number of diagonal notches 9 extending downwardly a suitable distance from the top edge of the bar, and between these end bars a central, intermediate, transverse bar 10 is provided in the frame which is fashioned with similar notches 11 in its upper edge. The diagonal notches in the end and intermediate bars are alined, three sets of notches being illustrated in the drawings for each frame, but it will be understood, of course, that the number of sets may be added and varied if desired.

The intermediate frame sections or square frames have in the upper edges of the opposed parallel bars 12 a series of diagonal notches 13 and these frames also have cross, central, intermediate bars 14 with diagonal notches 15 in their upper edges. The series of notches in the outer bars are alined with the series of notches in the intermediate bar of each frame, and it will be seen in Figure 1 that these frames may be used between the track rails with the intermediate bar 14 either parallel with the track rails or at right angles thereto, as desired. The trackside frames 3 and 4 are interchangeable, but the notched bars of these frames are always placed at right angles to the track rails.

A standardized rotary guard is adapted for use with any and all of the frames, said guard including a pipe or hollow shaft 16 having end collars 17 and fashioned with journals 18 at the extreme ends beyond these collars 17. At the longitudinal center of

the shaft is provided a pair of spaced collars 19 and 20 between which is provided a journal member 21. A spiral blade 22 is fashioned at one side of the center of the shaft and a similar spiral blade 23 is fashioned at the other end of the shaft.

These rotary guard members are standardized as to size, shape and material, and they may be cast as integral units, or otherwise fashioned, if desired, preferably with blunt edges to the spiral blades, made similar to the twist or worms of an auger, and smooth journals at 18 and 21; and the pitch of the spiral blades is preferably low in order that the spiral edges may be brought into proper close proximity.

After the rectangular frames have been laid and secured in proper position, each frame is supplied with its rotary guards, 20 the latter being placed preferably in transverse order in the frames with the journals 18 and 21 resting in complementary notches of the frames, and the guards are retained in place by their own weight. As indicated in Figures 1 and 2, the spiral blades of adjoining guards, at their edges, are brought into close proximity for the purpose of forming pockets between the spiral blades. It will be apparent that, should a cow attempt to step upon, or walk across, the appliance, the pressure of the hoof upon the freely rotatable guard will cause the latter to revolve, causing a forward or backward

and sidewise movement of the foot, thus insuring an insecure foot-hold, with consequent frustration of the attempt on the part of the animal to trespass upon the railroad.

It is obvious that a guard may be removed from its bearings by first elevating one end and then swinging, or rolling the guard free of its frame, in order to gain access to the road bed, and of course, all of the guards may be removed in this manner, if desired, and in case an animal jumps over a single unit, another unit may be added between the rails to making scaling impossible. If more than one track is to be guarded, the units should be extended across the parallel tracks with connecting units across and between the tracks.

Having thus fully described my invention, what I claim as new and desire to secure by Letters Patent is:—

A cattle guard comprising a pair of rectangular trackside frames and a rectangular between-the-rails-frame, the former having a length corresponding to the diametrical dimensions of the latter, said frames having notched end bars and notched intermediate bars, and sets of longitudinally and transversely extending interchangeable rotary guards having journals supported in said bars.

In testimony whereof I affix my signature.

ARTHUR J. SHAW.
